GEORGE S. GRANT, OF PROVIDENCE, RHODE ISLAND, ASSIGNOR
TO ALBERT O. BAKER, OF SAME PLACE.

Letters Patent No. 89,037, dated April 20, 1869.

IMPROVEMENT IN SNAPS FOR BRACELETS, &c.

The Schedule referred to in these Letters Patent and making part of the same

To all whom it may concern:

Be it known that I, GEORGE S. GRANT, of the city and county of Providence, in the State of Rhode Island, and have invented a new and useful Improvement on a Snap for Clasping Bracelets, Necklaces, &c., and I do hereby declare that the following is a full and exact description thereof, reference being had to the accompanying drawings, and to the letters and figures of reference marked thereon.

Heretofore there has been great inconvenience and loss occasioned by the facility with which the ordinary snaps or clicks on bracelets, necklaces, &c., become unclasped; and

The nature of my invention consists in providing an ordinary snap, with a locking-device, to prevent its ordinary unclasping, except by manipulation.

To enable others skilled in the art to make and use my invention, I will proceed to describe its construction and operation.

Figure 1 is a sectional transverse view of the snap and its frame with the spring locked.

Figure 2 is a sectional transverse view of the snap and its frame with the spring unlocked.

Figure 3 is a vertical sectional view of the snap, its frame, and its post.

In the post *a*, fig. 2, which is set loose in an ordinary snap-frame, a mortise or slot, *d*, fig. 2, is cut sufficiently long and deep to permit the ends of the spring

b, fig. 2, to approach each other, the post *a* being held in its position by the spring *b*, as in ordinary snaps.

Now, at the ends of the mortise or slot *d*, fig. 1, two other slots or mortises, *c' c''*, fig. 1, are cut at angles greater or less than right angles, as the case may be, so that when the post *a* is made to revolve in its bearings the end of the spring *b* and the edge of the plate or plane *g* enter the mortises or slots *c' c''*, as seen in fig. 1, and the post *a* cannot be depressed because held by the plane or plate *g*, in the mortise or slot *c''*; and the lip of the spring *b* is held at and in the mortise or slot *c'*, fig. 1, lest any jar might cause that to be depressed and the snap to be unclasped.

In fig. 1, the slot *e*, in the head of the post *a*, is merely an indicator to show whether the snap is locked or unlocked.

It is evident that this improvement can be applied not only to bracelet and necklace, but to many other articles, where the snaps are used, or can be used, with advantage.

What I claim as my invention, is—

The application of mortises or slots, or their equivalents, to the post of the snap, for the purpose of locking the snap, substantially as herein described.

GEORGE S. GRANT.
